UNITED STATES PATENT OFFICE.

MABEL BLACKMAN, OF NEW YORK, N. Y., ASSIGNOR OF ONE-HALF TO LILLIAN K. HOSIER, AND ONE-HALF TO ESTELLE MCKEE, BOTH OF NEW YORK, N. Y.

RECORD LIFTER FOR TALKING MACHINES.

Application filed October 21, 1921. Serial No. 509,232.

To all whom it may concern:

Be it known that I, MABEL BLACKMAN, a citizen of the United States, and a resident of New York city, in the county and State 5 of New York, have invented certain new and useful Improvements in Record Lifters for Talking Machines, of which the following is a full, clear, and exact description.

This invention relates to phonograph attachments and particularly to such a device employed for the purpose of assisting in removing the record disks from the turn table.

A particular object is to provide a device of the character described which can be 15 manufactured at low cost, can be conveniently attached to the turn table of a phonograph and will not be conspicuous.

Drawings.

20 Figure 1 is an elevational view of a part of a phonograph, the turn table thereof being shown in section to illustrate my record lifting attachment in conjunction therewith.

25 Figure 2 is an enlarged sectional view of a part of the turn table showing more clearly the record lifting attachment.

Figure 3 is a top plan view of my device, the top of the turn table being removed to 30 expose the downwardly extending flange thereon.

Figure 4 is a view of the device as seen in Figure 3 looking from the center of the turn table.

35 Figure 5 is a view of a modification of my device.

Description.

A phonograph denoted generally by 10 40 comprises the usual reproducer 11, turn table 12 and cabinet 13. The turntable is, in the usual construction, provided with a downwardly projecting flange 14 and a center journal member 15 which frictionally engages the motor shaft 16. The upper side 45 of the table is covered with felt 17 to prevent the record 18 from being scratched. The felt, being soft and closely adhering to the record makes it difficult for the person 50 removing the record to get a firm grip thereon, and the thinness of the record also makes it necessary to use the finger tips in raising the record which tears up the edge of the felt.

55 The record raising device comprises a U-

shaped clamp member 19 which is adapted to be slipped over the downwardly extending flange 14 of the table, and be held in position by a set screw 20, having a knurled head 21, in the portion of the clamp 19 that lies outside of the flange 14.

The inner portion of the clamp 19 is formed to comprise an ear 22 which has fulcrumed thereon the operating lever 23. The latter comprises a portion 24 that extends 60 downwardly from the pivot point adjacent the flange 14 and outwardly thereunder to form a widened knurled finger piece 25. The extension 26 of the portion 24 extends inwardly beneath and adjacent the under 70 surface of the table to an opening 27 in the latter, the opening also passing through the felt. The extension 26 is upturned as at 28 to form a record engaging finger. The lever 75 is constructed of wood or light metal so that the weight of the record will hold the same down.

In use, when it is desired to take hold of a record, a slight pressure on the finger piece 25 causes the finger 28 to move upwardly 80 through the opening and engage the under surface of the record to thereby raise it from the table.

In the modification illustrated in Fig. 5 use is made of a similar clamping member, 85 the ear thereon being outside the periphery of the table, and forming a fulcrum for the lever 29 which comprises a downwardly extending angularly disposed finger engaging member 30, and a horizontally disposed inwardly extending piece 31 which is normally adapted to nest beneath the record on the table, the felt being cut as at 32 to allow for the piece 31.

Pressure on the finger member 30 causes 95 the piece 31 to raise the record so that it can be firmly gripped by the fingers.

Claim.

The combination with a record holding 100 turntable of a phonograph comprising a downwardly extending flange; of a member comprising a clamp adapted to grip said flange, a lever pivoted to said clamp, a record engaging portion on said lever, and a 105 finger engaging member on said lever, said member when operated being adapted to cause said lever to partially raise the record from the turntable.

MABEL BLACKMAN.
